UNITED STATES PATENT OFFICE.

JOSHUA B. BARNES, OF SPRINGFIELD, ILLINOIS.

DESIGN FOR A WRENCH FOR STAY-BOLTS FOR BOILER-SHEETS.

SPECIFICATION forming part of Design No. 34,838, dated July 23, 1901.

Application filed June 8, 1901. Serial No. 63,803. Term of patent 14 years.

To all whom it may concern:

Be it known that I, JOSHUA B. BARNES, a citizen of the United States, residing at Springfield, Illinois, (whose post-office address is the same,) have invented and produced a new and original Design for Wrenches for Stay-Bolts of Boiler-Sheets, of which the following is a full, clear, and exact specification.

In the accompanying drawings, Figure 1 is an elevation of the wrench, showing it from one side. Fig. 2 is a like view showing the wrench a quarter-turn from the position of Fig. 1. Fig. 3 shows the wrench in end elevation, while Fig. 4 is an elevation of the opposite end.

The leading feature of the design is in the configuration. The body of the wrench has a double taper with an enlarged central portion, and, as shown in Fig. 1, there is an open-

ing *a* passing through from side to side with a ²⁰ taper part *b*, extending from the position of the opening to the end of the wrench, where a squared projection *c* is formed, as also shown in Fig. 4. Adjacent to the opening *a* there is a second opening *d*, extending at right ²⁵ angles to the opening *a*, and from the position of this opening extends a taper *e*, and at the end of the portion is a squared projection *f* of less diameter than the end of the tapered section *e*, as shown in Fig. 3. ³⁰

I claim—

The design for a wrench as herein shown and described.

JOSHUA B. BARNES.
